(57) **CLAIM**

The ornamental design for a leg exercise equipment as shown and described.

DESCRIPTION

FIG. 1 is a top, front, left side perspective view of a leg exercise equipment showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled "9" in FIG. 1;

FIG. 10 is an enlarged view of the portion labeled "10" in FIG. 7;

FIG. 11 is an enlarged view of the portion labeled "11" in FIG. 1; and,

FIG. 12 is an enlarged view of the portion labeled "12" in FIG. 1.

The broken lines show the features of the leg exercise equipment that form no part of the claimed design. Dot-dash broken line circle frames define the boundary of an enlarged view and form no part of the claimed design.
